Primary Examiner — Catherine Tuttle(74) *Attorney, Agent, or Firm* — Frank Marino(57) **CLAIM**

The ornamental design for a throwing target, as shown and described.

DESCRIPTION

FIG. 1 is a perspective view of a throwing target showing my new design with its tiltable circular ring slightly tilted;
 FIG. 2 is a front elevation view of the throwing target of FIG. 1 with its tiltable circular ring vertically disposed;
 FIG. 3 is a top view of the throwing target of FIG. 1 with its tiltable circular ring vertically disposed;
 FIG. 4 is a rear elevation view of the throwing target of FIG. 1 with its tiltable circular ring vertically disposed; and,
 FIG. 5 is a right side elevations view of the throwing target of FIG. 1 with its tiltable circular ring vertically disposed, the left side elevation view thereof being a mirror image thereto. The bottom view forms no part of the claimed design. The broken lines are included for the purpose of illustrating the portions of the throwing target that form no part of the claimed design.
